UNITED STATES PATENT OFFICE.

ADOLF BALENSIEFER, OF NEW YORK, N. Y.

BREAKDOWN GUN.

SPECIFICATION forming part of Letters Patent No. 530,467, dated December 4, 1894.

Application filed March 8, 1894. Serial No. 502,848. (No model.)

To all whom it may concern:

Be it known that I, ADOLF BALENSIEFER, a citizen of the United States, residing at New York, in the county and State of New York, have invented new and useful Improvements in Breech-Loading Firearms, of which the following is a specification.

This invention has for its objects to provide a new and improved fire arm, the parts of which can be readily detached and the barrel utilized as a cane or walking stick, and to provide novel means for cocking and releasing the firing needle.

To accomplish these objects my invention consists in the features of construction and the combination or arrangement of parts hereinafter described and claimed, reference being made to the accompanying drawings, in which—

Figure 1 is a side elevation of the fire arm. Fig. 2 is a plan view (enlarged) of part of Fig. 1 and showing the catch open to let the barrel drop. Fig. 3 is an inverted plan view of Fig. 2. Fig. 4 shows the barrel serving as a cane. Fig. 5 is a sectional side elevation showing the arm discharged. Fig. 6 is a view similar to Fig. 5 showing the barrel dropped. Fig. 7 is a view similar to Fig. 5 showing the parts ready or firing.

The gun barrel *b* has a screw thread 14 to which can be screwed a button or handle *a* (Fig. 4) the muzzle *h* being provided with an end or ferrule portion *i* when the barrel is to serve as a cane. The screw thread 14 enables the barrel to be connected to the cartridge chamber *g* jointed or pivoted at 12 to the breech portion *k* having a breech block *c* and from which extends a tube 4.

The barrel *b* is held up by a spring or catch 10 engaging a stud *l* and when the catch 10 is withdrawn or released (Fig. 2) by the lever 8 fulcrumed to the lugs 9 of the catch 10, the barrel *b* is free to drop (Fig. 6). In this position a cartridge *f* can be withdrawn by the extractor 11 and a fresh cartridge inserted.

The cartridge extractor 11 is prevented from becoming detached by the screw 17 passing through a suitable slot in the extractor to allow the latter sufficient play.

In the tube 4 is a firing pin or hammer 1 having a split or forked spring tail guided in

a ring or way 3 secured to the tube 4 by a screw 7. Braced against the ring or guide 3 and against a collar *m* on the pin 1 is a spring 2 which tends to give the firing stroke to the pin. 55

The split tail of the pin 1 has a lug or shoulder *n* adapted to engage the guide 3 (Figs. 6 and 7) to hold the pin cocked. The trigger 5 is adapted to move the shoulder *n* out of engagement with the guide 3 so that 60 the spring 2 can actuate the pin 1.

To the cartridge chamber at *o* is jointed an arm or lever 13 adapted to engage or strike against the collar or projection *m* of the pin 1 as seen in Fig. 5. When the barrel *b* is 65 dropped (Fig. 6) the arm 13 acting on the collar *m* will force back or cock the pin 1. The trigger 5, the free end of which is split or composed of spring blades can be held out of the way when desired by having its free end 70 jammed or held between lugs *p* (Fig. 3). The free end of the arm 13 may be held in proper position by a spring *q* suitably secured to the gun barrel or cartridge chamber.

Onto the tube 4 is slipped a wooden sleeve 75 or shell 6 and said tube 4 has internal and external screw threads 15 and 16 (Fig. 6). To the screw thread 15 is secured the handle *d*, Fig. 5, and to the screw-thread 16 is secured the stock *e* having a form similar to that of 80 an ordinary shoulder gun.

The various parts of the fire arm can be readily dismounted or detached and the construction of the arm is simple so as to be reliable in operation and readily repaired when necessary. 85

What I claim as new, and desire to secure by Letters Patent, is—

1. A swinging or drop down gun barrel, combined with a firing needle having a forked 90 or split spring tail provided with a shoulder, a ring or guide adapted to be engaged by the shoulder to hold the needle cocked, and an arm actuated by the barrel and adapted to engage the needle for cocking the latter when 95 the barrel is dropped substantially as described.

2. A gun barrel combined with a firing needle having a forked or split spring tail provided with a shoulder, a ring or guide 100 adapted for the engagement of the shoulder to hold the pin cocked, and a trigger adapted

to engage the tail for freeing the latter substantially as described.

3. A swinging or drop down gun barrel, combined with a firing needle having a collar and a forked or split spring tail provided with a shoulder, a guide for the tail said guide being adapted for engagement by the shoulder to hold the pin cocked, an actuating spring for the pin said spring being braced between the guide and collar, and an arm actuated by the barrel and made to engage the collar for cocking the needle when the barrel is dropped substantially as described.

4. A gun barrel provided with a tube at its breech portion, said tube having an internal and an external screw thread, a stock secured to one of said screw threads, and a handle se-

cured to the other screw thread, substantially as described.

5. A gun barrel provided with a tube at its breech portion, said tube having an internal and an external screw thread, a stock secured to one of said screw threads, and a handle secured to the other screw thread, combined with a firing needle housed in said tube substantially as described.

In testimony whereof I have hereunto set my hand in the presence of two subscribing witnesses.

ADOLF BALENSIEFER.
